UNITED STATES PATENT OFFICE.

GEORGE T. BOND, OF HUNTINGTON, WEST VIRGINIA.

BRAKE-SHOE.

1,282,739.

Specification of Letters Patent. Patented Oct. 29, 1918.

Application filed January 19, 1918. Serial No. 212,622.

To all whom it may concern:

Be it known that I, GEORGE T. BOND, a citizen of the United States, residing at Huntington, in the county of Cabell and State of West Virginia, have invented certain new and useful Improvements in Brake-Shoes, of which the following is a specification, reference being had therein to the accompanying drawings.

- 10 This invention relates to car brake-shoes of compound type that include friction or wearing members, which contact with the wheel-treads, and holders, which maintain the shoes on brake-heads. The invention 15 provides means, as hereinafter set forth, whereby the shoe parts are held together in such manner that they may be assembled and disassembled without injury to the holder. The two members thus associated 20 form a unitary shoe, which is attached to the brake-head in the usual manner of shoes in general use.

The invention has in view the provision 25 of a brake-shoe that will be more economical in service than a reinforced or backed shoe of the usual form, which has to be removed and entirely scrapped when only a little more than half worn, because of liability of the wheel wearing through into the brake- 30 head and thereby damaging it. It is to overcome this objection that the shoe is formed in the particular manner contemplated by the invention and to make the backs or holders available for subsequent use 35 on new friction or wearing members.

The brake-shoe provided by the invention is simple to manufacture, its parts can be assembled quickly and easily and without the necessity of employing special tools, and 40 the cast friction or wearing member can be cleaned of adhering mold-sand and handled and transported without liability of damage of its parts.

My co-pending application Ser. No. 45 212,620, filed January 19, 1918, discloses forms of multiple-keeper and standard brake-shoes, with similar objects in view, in which threaded fasteners are employed to maintain the holding and wearing members 50 together. The present invention is directed

more particularly to removable fasteners, other than those of threaded types, for maintaining the holding and wearing members in unitary association as complete shoes, the fasteners being easily brought to and removed from the parts, and the invention provides forms thereof adapted for use with shoes of both the standard and multiple-keeper types.

When read in connection with the description herein, the features of the invention will be apparent from the accompanying drawings, forming part hereof, wherein embodiments of the invention are disclosed, for purposes of illustration.

While the disclosures herein now are considered to exemplify preferable embodiments of the invention, it is to be understood that it is not the intention to be limited necessarily thereto in interpretation of the claims, as alterations within the limits of the claims can be made without departing from the nature and spirit of the invention.

Like reference-characters refer to corresponding parts in the views of the drawings, of which—

Fig. 1 is a side elevation, partly in section, of a multiple-keeper brake-shoe assembled and in place on a brake-head;

Fig. 2 is a fragmentary view of the rear side of the wearing member;

Fig. 3 is a transverse sectional view on the line III—III, Fig. 1;

Fig. 4 is a fragmentary plan view of a wearing member illustrative of another form of fastener;

Fig. 5 is a transverse sectional view illustrative of the form of fastener shown by Fig. 4;

Fig. 6 is a fragmentary side elevation, partly in section, showing a form of removable fastener insertible into the face of the wearing member and adapted for use in a shoe for service on a standard brake-head;

Fig. 7 is a plan view showing in part the holder and in part the wearing member of the form shown by Fig. 6;

Fig. 8 is a fragmentary transverse sectional view on the line VIII—VIII, Fig. 7;

Fig. 9 is a fragmentary side elevation, 10

- partly in section, showing a form of removable fastener insertible from the sides into the wearing member and adapted for use in a shoe for service on a standard brake-head;
- 5 Fig. 10 is a plan view showing in part the holder and in part the wearing member of the form shown by Fig. 9;
- Fig. 11 is a fragmentary transverse sectional view on the line XI—XI, Fig. 10 and
- 10 Fig. 12 is a perspective of the fastener.
- In all of the views in which those parts appear, 1 designates a brake-head, 2 designates the recesses or seats or mortises formed therein for reception of a keeper 3 of a malleable or otherwise suitably formed
- 15 brake-shoe back or holder 4 secured to a wearing member 5, and 6 designates a retaining-key disposed in longitudinal openings 7 in the brake-head and 8 in the keepers,
- 20 the key and keepers maintaining the shoe on the head in a manner well known in the art.
- In order that a worn wearing member may be removed from a holder and the latter again used successively in association with
- 25 new wearing members, the invention provides fasteners that may be placed in position in the wearing member when it is desired to associate it with a holder. The arrangement is such that the fasteners will
- 30 lock the holder and wearing member together and that the holder will prevent the fasteners from moving to such positions as would permit of their withdrawal from the wearing member.
- 35 Figs. 1, 2, and 3 disclose an arrangement of bendable fasteners 9. A fastener of this kind preferably is formed from malleable sheet metal bent upon itself to form a foot
- 40 and an intermediate double-limbed shank 11.
- The wearing member is formed in its back or holder abutting face with recesses 12, each of a length and breadth to permit the foot
- 45 of a fastener to be placed therein. A passageway 13 extends from each end of the recess 12, its bottom lying in the same plane as the bottom of the recess, and it being of such dimensions as will permit the entrance of the foot fairly snugly thereinto. A slot
- 50 14, opening to the passageway and to the back of the wearing member, similarly extends from midway of each end of recess 12. Ordinarily two recesses 12 will be located between each two adjacent places of
- 55 contact of the wearing and holding members, and the passageways and slots will extend into transverse ribs or protuberances 15 constituting such contact places, so that one recess will serve for insertion and removal of
- 60 two fasteners.
- The back or holding member has openings 16 located in positions corresponding to the location of the slots 14 and of a dimension to receive fairly snugly the projecting por-

tions of the shanks 11. When a wearing member and a holder are to be assembled to form a shoe, fasteners are placed in the recesses 12 and slid into the passageways and slots extending therefrom. Then the shanks of the fasteners are passed into the openings 70 of the holder, and the two limbs of each shank are bent downwardly against the outer face of that member, whereby the two parts of the shoe are locked together.

In order to relieve the fasteners of the 75 shearing stresses imposed upon the wearing member by contact of the tread of a moving wheel, each abutting portion of the back is formed with an opening or seat 17, which takes a correspondingly-positioned protuberance or projection 18 of the wearing member. These protuberances project outwardly of the holding member a distance approximately the same as the thickness of the bent-down limbs of the shanks of the fasteners 85 9, and, when the shoe is in place on a brake-head the head rests against these protuberances and bent-down portions of the shanks and operates to maintain the latter against bending from locking position.

90 Figs. 4 and 5 disclose a single-footed type of fastener 19, which is formed of malleable sheet metal bent to form a laterally-extending foot 20 and a web 21. For each such a fastening, recesses 12 and passageways 13 95 are provided in the wearing member in a manner similar to those for the previous form, but the slots 14 extend from one side of the passageways to the face of the wearing member, in order to conform to the 100 shape of the fasteners.

With this form of fastener, the openings 16 of the back or holding member are of dimensions corresponding to those of the webs 21. The fasteners are placed in the 105 wearing member and passed into the openings of the holder in the same manner as with the previous form, and the projecting portions of the webs are bent downwardly against the face of the holder and 110 the two parts of the shoe thereby locked together. Preferably, the webs are of a thickness substantially that of the projection of protuberances or projections 18 and with them the bent-down portions of the 115 webs constitute contact places for the brake-head, which maintains the webs against bending from locking positions.

A form of fastener adapted for use in a shoe for service on a standard brake-head, 120 and which is insertible in recesses, passageways, and slots similar to those for the type of Figs. 4 and 5, is disclosed by Figs. 6, 7, and 8. Such a fastener 22 has a laterally-extending foot 23 and a web 24, which 125 latter has a head that is enlarged by a bendable lip 25 extending before bending in the plane of the web.

With this form of fastener, the openings 16 of the back or holder are of dimensions corresponding to those of the heads of the webs. The fasteners are placed in the wearing member and passed into the openings of the holder in the same manner as with the previous forms. After this is done, the lips 25 are bent laterally away from the openings 16 and over the face of the holder. 10 The lower edges of the lips incline downwardly from the ends to the webs proper, as shown at 25^a, and the webs are just of such length that, when the lips are bent, the inclined edges thereof will have wedging 15 action against the holder and tightly bind it to the wearing member.

A fastener somewhat similar to that of Figs. 6, 7 and 8, but adapted more particularly to be placed laterally into the holding member, is disclosed by Figs. 9, 10, 20 11 and 12. This fastener 26, like that of the other types, is formed of malleable metal cut to produce an enlarged foot 27, a web 28, and a head enlarged by a lip 29, all lying 25 in the same plane before bending. After cutting, the foot is bent to lie in a plane substantially at right angles to that of the web, as seen in Fig. 11.

For each of such fasteners to be used, the 30 wearing member is formed with a slot 30 extending from one side inwardly and opening to the back-abutting face of the member. The slots correspond in cross section to the planetary shape of the fasteners—that is, 35 they are larger at the bottom to receive the enlarged feet 27 and smaller at the top to correspond to the webs 28—and the series of slots are arranged alternately so that no two immediately adjacent slots open to the 40 same side of the wearing member.

With this form of fastener, the openings 15 of the back or holder are of dimensions corresponding to those of the heads of the webs. The fasteners are inserted into the 45 slots 30 and brought to the inner ends thereof. The holder is placed against the wearing member with the fasteners extending through the openings 16, and the lips 29, which are of a form similar to the lips 25 of 50 a previously-described form, are bent laterally away from the openings 16 and over the holder and thereby caused to bind that member against the wearing member.

In all of the forms herein exemplified, 55 the seats 17 of the holder and protuberances 18 of the wearing member prevent relative slipping movement of those parts and thereby movement of the fasteners to positions of withdrawal from the wearing member also is prevented.

Having thus described my invention, what I claim as new, and desire to secure by Letters Patent, is—

1. In a brake-shoe wearing member ar-

ranged for association with a holder having 65 an opening, a lug comprising a shank removably secured to the member and extending from the rear face thereof and having a portion arranged to be bent over after being passed through the holder-opening 70 whereby to maintain the wearing member and holder together.

2. In a brake-shoe wearing member arranged for association with a holder having 75 an opening, an elongated malleable sheet metal lug comprising a shank removably secured to the member and extending from the rear face thereof and a portion arranged to be bent laterally after being passed into the holder-opening whereby to maintain the 80 wearing member and holder together.

3. A brake-shoe wearing member arranged to have a fastener with an enlarged foot and a shank associated therewith to maintain it on a support, said member having 85 in its rear side a recess arranged to receive the fastener-foot and a passageway for the foot and a slot for the fastener-shank extending from said recess.

4. A brake-shoe wearing member arranged to have fasteners with enlarged feet and shanks associated therewith to maintain it on a support, said member having 90 contact places raised above the plane of its rear face and passageways for the feet and 95 slots for the shanks of the fasteners extending into said contact places.

5. In a brake-shoe, a wearing member having in its rear side a passageway and a slot, a protuberance on the rear side of said 100 member, a holder abutting said side of the wearing member and having a seat into which said protuberance extends and a holder-opening, and a bendable fastener in said passageway and slot having a shank 105 extending through said holder-opening and bent over against the outer face of the holder, whereby the wearing member and holder are held together, said fastener before engagement with the holder being movable into and out of said passageway and slot.

6. In a brake-shoe, a wearing member having in its rear side a recess and a passage-way and a slot leading from the recess, 115 a protuberance on the rear side of said member, a holder abutting said side of the wearing member and having a seat into which said protuberance extends and a fastener-opening, and a bendable fastener in 120 said passageway and slot having a shank extending through said holder-opening and bent over against the outer face of the holder, whereby the wearing member and holder are held together, said fastener before engagement with the holder being seatable in said recess and movable therefrom 125 into said passageway and slot.

7. The combination of a brake-head having contact places, a holder abutting said contact places and having fastener-openings and seats at the places of contact, means whereby the holder is maintained on the brake-head, a wearing member abutting said holder and having protuberances extending into said seats and slots with enlarged inner ends

aligned at their open ends with said fastener-openings, and fasteners in said slots extending through said fastener-openings and bent over and extending under the contact places of the brake-head. 16

In witness whereof, I have affixed my signature.

GEORGE T. BOND.
